UNITED STATES PATENT OFFICE.

HENRY C. KARR, OF WASHINGTON, DISTRICT OF COLUMBIA.

WATCH-HOLDING CLOCK-CASE.

No. 919,879.

Specification of Letters Patent.

Patented April 27, 1909.

Application filed February 25, 1908. Serial No. 417,671.

To all whom it may concern:

Be it known that I, HENRY C. KARR, a citizen of the United States of America, and resident of Washington, District of Columbia, have invented certain new and useful Improvements in Watch-Holding Clock-Cases, of which the following is a full and clear specification, reference being had to the accompanying drawing, in which—

10 Figure 1 is a face view of my improved case inclosing a watch of ordinary construction; Fig. 2 is a similar view with the front section removed; Fig. 3 is a vertical sectional view of the same; Fig. 4 is a detailed perspective of one of the two sections composing the case.

The object of this invention is to provide a simply constructed sectional casing in which a watch may be inclosed in such a 20 manner that it shall be converted into a small clock suitable for use as a traveling clock or for desks, bureaus, and so forth, without destroying the use of the time-piece as a watch.

25 In the preferred, but not the only, embodiment of my invention the case consists of two metal or other rigid sections *a* and *b* approximately rectangular in shape and adapted to telescope one within the other. In the 30 front wall of the outer section *a* is formed a circular opening whose edge is preferably bent or beveled inwardly to form a sort of bezel *a'*, while the back wall of the inner section is preferably closed entirely and provided with a circular central depression *b'*. The front of the inner section is entirely open and the back of the outer section is entirely open so that the two sections may be readily 35 telescoped one into the other to form a rectangular casing. The marginal walls of the two sections are approximately the same depth so that when the sections are put together the bottom and top and side walls of the casing are of double thickness their full 45 width.

The top wall of each casing section is provided with an open transverse slot *c* which when the sections are telescoped register with each other and form an opening up through 50 which the crown-carrying stem of the watch projects, the edges of the slots being made thereby to engage the stem of the watch at a point between the case thereof and the ring. In this way the watch is entirely incased except the winding stem and the bow or suspending ring, whereby the clock may be readily

hung up as well as wound or set without removing the watch from the case.

To inclose the watch in the casing it is simply necessary to first place it in the inner 60 section with its stem in the slot *c*, and then slide this section into the front or outer section, thus causing the registering slots to lock the stem in place and hold the watch in an upright position with its face coincident 65 with the opening in the front of the casing.

The two sections fit each other closely so that they are frictionally held together, thereby avoiding the necessity of employing 70 hinges and separate locking devices, while at

the same time permitting the sections to be readily separated at will. The two registering slots are approximately the same depth so that when the sections are slid together 75 the inner edges of the slots closely clasp the watch stem and center the watch in the case, the inner or bottom edges of the slots being curved to conform to the cylindrically-shaped stem. It will be observed also that

the edges of the slots engage an annular 80 shoulder on the watch-stem and thus serve to still further brace and steady the watch in a rigid upright position.

It will be observed further that the width of the case is such as to fit against the edges 85 of the watch, so as to prevent lateral edge-wise movement of the watch; and to prevent the lower portion of the watch shifting or vibrating forwardly and backwardly the central inward projection *b'* on the inner section 90 and the bezel or flange *a'* on the outer section clamp the watch firmly between them when the sections are slid together. These clamping projections on the front and back walls not only clamp the watch centrally of the 95 case but also enable the case to be made sufficiently deep to stand erect without propping, as is obvious.

As shown, the inclined annular flange *a'* fits against an annular shoulder on the face of the watch, preferably the shoulder formed by the edge of the crystal or the crystal-holding bezel, and thus assists in centering the watch with respect to the face-opening in the case. 100

It will be observed that the opening provided for exposing the watch-dial serves the additional function of a push-opening in separating the sections; it being necessary in separating the sections to simply hold the outer section and press backwardly upon the 105 crystal of the watch, whereupon the inner section carrying the watch will readily slide

backwardly out of the front section. It will be seen that this method of separating the sections is rendered of importance by reason of the fact that the inner section telescopes 5 practically entirely within the outer section and there is therefore no projecting portion thereof to take hold of in separating the sections, and it is further advantageous in view of the fact that by thus providing an easy 10 means of separating the sections I may dispense entirely with extraneous fastening devices and use instead the frictionally-engaged telescoping sections.

Having thus fully described my invention, 15 what I claim as new, and desire to secure by Letters Patent, is:—

1. A case for converting a watch into a clock, consisting of two flat-bottomed open shells frictionally fitted one entirely within 20 the other, the top walls of the two sections being notched coincidently to embrace the stem of the watch, and the face of the outer section being provided with a circular opening 45 for the purposes set forth.

2. A case for converting a watch into a clock, consisting of two hollow sections having a flat base and telescoped one into the other, the two sections frictionally engaging each other to avoid extraneous fastening 50 devices and the upper walls of both sections

being provided with open-ended registering slots to permit the stem of the watch to extend outside of the casing, one of the sections being provided with a central circular opening whose annular edge is bent inwardly to form a rest for the face of the watch while the back wall of the other section is bent inwardly to form a rest for the back of the watch.

3. A case for converting a watch into a 40 clock, consisting of two flat-bottomed shells frictionally slidable one into the other and having the edges of their top walls centrally notched coincidently to embrace the stem of the watch between the case thereof and 45 the ring, and the face of the outer section being provided with a central opening adapted to serve both as a sight-opening and as a push-opening in separating the sections, said opening having its edge turned inwardly to form a 50 bearing for the face of the watch when the same is clamped between the front and back walls of the case.

In testimony whereof I hereunto affix my signature in the presence of two witnesses 55 this 25th day of February 1908.

HENRY C. KARR.
